UNITED STATES PATENT OFFICE.

THOMAS LEA, OF EL PASO, TEXAS.

PAPER-CLIP.

1,314,818.

Specification of Letters Patent. Patented Sept. 2, 1919.

Application filed March 5, 1918, Serial No. 220,461. Renewed July 24, 1919. Serial No. 312,983.

To all whom it may concern:

Be it known that I, THOMAS LEA, a citizen of the United States, residing at El Paso, in the county of El Paso and State of Texas, 5 have invented certain new and useful Improvements in Paper-Clips, of which the following is a specification.

This invention has relation to paper clips or the like, and has for an object to provide 10 a device for holding together loose papers in a positive and firm manner, and which is extremely simple in construction, permitting ease of manipulation and the manufacture thereof at a greatly reduced cost.

15 Another object of the invention is to provide a paper clip having the above described characteristics, and which is formed of a single piece of metal which may be in the nature of a stamping.

20 In addition to the foregoing, this invention comprehends improvements in the details of construction and arrangement of parts, to be hereinafter described and particularly pointed out in the appended claim.

25 In the accompanying drawings, in which similar and corresponding parts are designated by the same characters of reference throughout the several views in which they appear;

30 Figure 1 is a view of my improved clip illustrating its application.

Fig. 2 is a view thereof in edge elevation.

Fig. 3 is a view of the clip in end view, and

35 Fig. 4 is a view thereof in section.

With reference to the drawings, 10 indicates a strip of metal from which the clip is formed. The clips may be stamped out of a sheet in the blank form and subsequently bent into proper formation in a manner which will be presently seen.

The strip is formed at each end with transverse extensions, one extension being designated 11 and the other 12. The strip 40 is bent at a point intermediate its ends to

form a relatively large and almost circular loop 13 whereby to bring the extensions 11 and 12 in contact and contiguous relation

thereby forming jaws between which the paper is gripped. It will be noted that 50 while the jaws are of the same length one is of a greater width than the other, the wider jaw being the one indicated in the present instance at 12. The ends of the wider jaw are furthermore bent away and out of contact with the other jaw as at 14.

Thus it will be seen that I have provided a new and useful form of paper clip which has the advantage in that it, being formed of a single piece of metal, may be manufactured cheaply. It will be noted that the provision of the loop 13 adds to the utility of the device by increasing the resiliency of the clip and by permitting the jaws to be separated to a considerable distance to 65 receive a large number of papers therebetween. The separated ends of the jaws also permits the papers to be readily engaged between the jaws.

While I have illustrated and described 70 my invention with some degree of particularity, I realize that in practice various alterations therein may be made, and I therefore reserve the right and privilege of changing the form of the details of construction and arrangement of the correlated 75 parts, without departing from the spirit of the invention and the scope of the appended claim.

Having thus described my invention, what 80 I desire to secure by United States Letters Patent is:

An article of manufacture comprising a strip of material having its ends terminating in oppositely disposed extensions of different widths with certain corners of the wider extension directed outwardly and the opposed surfaces of the extensions bent in contact with one another.

In testimony whereof I affix my signature 90 in the presence of two witnesses.

THOMAS LEA.
